Application October 14, 1936, Serial No. 105,488

10 Claims. (Cl. 105—409)

This invention relates to improvements in closed top railway car bodies and it consists of the matters hereinafter described and more particularly pointed out in the appended claims.

The closed top body with which the present invention is more particularly concerned is one especially adapted for use as the body for a so-called railway "box" car.

One of the objects of the present invention is to provide a closed top, sheet metal body for a railway car, which, though light in weight, because of the distribution of the metal and coordination of the parts whereby a mutual bracing effect is obtained, is strong and rigid.

Another object of the invention is to provide a body of this kind which may be produced at a low material and labor cost.

A further object of the invention is to provide a car body of this kind including a pair of similar structural units, each forming a side and a longitudinal half of the roof and which units are so formed that they may be readily fabricated and then shipped, without damage, to the place of assembly with associated end structures.

Still another object of the invention is to provide a car body of this kind wherein the sheathing for the side is formed to provide such stiffness for the side of the body as to eliminate the necessity of side posts and to give more interior width to the body, without exceeding the allowable outside width of the body.

Still a further object of the invention is to provide a sheet metal car body having a novel arrangement of parts along the bottom portion of its sides, whereby its rust-resisting qualities and strength are increased at that point and whereby its repair-free period of usefulness is prolonged.

Again, it is an object of the invention to provide a simple and strong structure at the eaves of the body, whereby the side and associated roof parts are rigidly connected together.

It is also a further object of the invention to provide a novel sheathing for the side of the body, which is buckling resisting and which eliminates the use of side posts.

Again, it is another object of the invention to provide a novel ridge arrangement for the body which is not only tight and leakproof, but is of such simple construction, that it can be easily assembled.

The above mentioned objects of the invention, as well as others, together with the advantages thereof will more fully appear as I proceed with my specification.

In the drawings:

Fig. 1 is a view in side elevation of a closed top railway car body embodying therein the preferred form of the invention.

Fig. 2 is a transverse vertical sectional view through a part of the car body as taken on the line 2—2 of Fig. 1.

Fig. 3 is a longitudinal horizontal sectional view through a part of one side and one end of the body as taken on the line 3—3 of Fig. 1.

Fig. 4 is a detail vertical sectional view on an enlarged scale through a sill portion of the body as taken on the line 4—4 of Fig. 1.

Fig. 5 is another detail vertical sectional view on an enlarged scale through the side plate portion of the body as taken on the line 5—5 of Fig. 1.

Fig. 6 is a further detail vertical sectional view also on an enlarged scale through the ridge portion of the car body roof as taken on the line 6—6 of Fig. 1.

Fig. 7 is a detail vertical sectional view on an enlarged scale, through one of the carlines and associated roof sheets as taken on the line 7—7 of Fig. 2.

Fig. 8 is a detail longitudinal horizontal sectional view through a part of the body, on an enlarged scale as taken on the line 8—8 of Fig. 2.

Fig. 9 is a detail vertical longitudinal sectional view through a part of the body as taken on the line 9—9 of Fig. 2.

The closed top railway car body of the kind described herein, is formed of four units, namely a pair of longitudinal units each forming a side and a longitudinal half of the roof and a pair of end units, the said units having meeting edges adapted to be connected together. The present invention is more particularly concerned with the structure of the unit forming one side and a longitudinal half of the roof.

Referring now in detail to that embodiment of the invention illustrated in the drawings, 10—10 indicate as a whole, one of a pair of longitudinal units of the body and 11 indicates, as a whole, one of a pair of end units associated with the longitudinal units to form the body.

Each unit 10 includes a longitudinally extending sill member 12, a longitudinal side plate 13 and a longitudinal ridge member 14. The sill member is made from a so-called "bulb" angle used in car building and includes a vertical flange 15 and an inwardly extending top horizontal flange 16. The side plate 13, as herein shown, is a Z bar and includes a horizontal web 17, an inner downwardly extending vertical flange 18 and an outer upwardly extending, inwardly curved

flange 19. The ridge member 14 is preferably an angle bar with a vertical flange 20 facing upwardly and a horizontal flange 21 facing outwardly and slightly downwardly.

5 25 indicates, as a whole, the longitudinally spaced carlines of the unit, which extend downwardly and outwardly, from the ridge member 14, toward the side plate 13. As herein shown, each carline has an inverted channel cross section 10 and includes a top web 26 and downwardly and outwardly extending side flanges 27-27, each having an out-turned margin 28. This channel cross sectional shape makes it possible to use a light gauge metal in the carline so that the weight 15 is reduced to a minimum without sacrificing strength. The inner end of each carline is disposed under the flange 21 of the associated ridge member and is secured thereto as will later appear. The outer end of the carline is made on a 20 curve conforming to the curvature of the flange 19 of the associated side plate. The web 26 of each carline stops short of said plate flange while the flange margins 28-28 thereof are made as extensions 29 that overlap the inner face of the 25 inner flange 18 of the plate and are secured thereto as will soon appear.

In the outer end of each carline is a rigidifying or bracing knee 30 also of a channel-like cross section and including a web 31, side flanges 32-32 30 and an end wall 33. The web 31 of the knee engages the inner face of the web of the carline. The end wall 33 extends from the web to terminate as a flared out tail piece 34 engaged between the inner face of the side plate flange 18 and 35 flange extension 29 of the associated carline. The manner of fastening the tail piece of the knee to the side plate and the manner of fastening the web 31 to the web of the carline will appear later.

Associated with the sill of each unit 10 is a 40 thick riser plate 35. As shown herein, said riser plate is so disposed that its outer face is flush with that of the vertical flange 15 of the sill. One way by which the riser plate may be attached 45 is to offset the bottom margin 36 thereof at an inward and downward angle. When the edge of said margin is engaged on the horizontal flange of the sill 12 and the outer face of the riser plate is disposed in the plane of the outer face of the flange 15 of the sill, this provides a groove in 50 which a line of weld 38 is laid to substantially fill said groove.

39 indicates as a whole, the side sheathing for the unit. As shown herein the sheathing comprises vertically disposed relatively thin metal sheets 40. Each sheet, except those on each side 55 of the door opening, is formed along one margin to provide an inturned, right-angled stiffening rib 41 including a flange 42. This rib is herein shown to be as deep as the furring strips 43 for the lining 44 and the depth of said rib is less than 60 the depth of the web 17 of the side plate. That margin of each sheet 40 opposite the stiffening rib is left straight and is made to overlap the first mentioned margin of the next adjacent sheet 65 and is secured thereto as by a line of rivets 45.

The bottom margin of each sheet 40 overlaps the outer face of the top margin of the riser plate 35 while the stiffening rib 41 of said sheet terminates short of the top edge of the riser 70 plate. To add rigidity to the connection of the sheets with the riser plate, I provide an angle gusset plate 46 with one flange riveted to the rib 41 of the sheet and with the other flange overlapping the inner face of the top margin of the 75 riser plate 35. Rivets 47, extend through the bot-

tom margin of the sheet, the top margin of the riser plate and the associated flange of the gusset plate. By means of this plate 46, a rigid connection is afforded between the sheet and the side sill through the riser plate. The riser plate, being relatively thick, withstands the corrosive effects of fluids used in cleaning the floor of the car, of which the unit forms a part.

The top end of the sheet 40 extends into a position and is curved to overlap the outer flange 10 19 of the side plate to which said end of the sheet is attached by rivets 47. The top end of each stiffening rib is cut off below the side plate. A bracket having vertical and horizontal legs 48-49 is provided as a means attaching the side 15 plate and the ribs 41 together. As herein shown, the vertical flange of the bracket is riveted as at 50 to the top end of the rib and the horizontal leg 49 engages the outer face of the inner flange of the side plate. A rivet 51 passes through the flange 49, the flange 18 and a part of the tail 20 piece 34 of the knee 30 to secure all of these parts together. Also, a rivet 52 passes through the flanges 49 and 18, the tail pieces 34 and one of the 25 extensions 29 of the carline. A third rivet 53 is employed to secure the other extension of the carline along with the tail piece 34 of the knee 30 brace to the flange 18 of the side plate. It is apparent that by reason of the structure described, the parts mentioned are rigidly secured to the side plate and are so coordinated as mutually to 30 coact therewith to provide the stiffness and strength required at this point without undue weight.

54-54 indicates the roof sheets of the units 35 and which are of thinner stock than that employed in the side sheets. These roof sheets have marginal parts which overlap in the planes of the carlines as best appears in Fig. 7 and rivets 55 pass through the said overlapping marginal 40 parts and through the web 26 of the carlines to secure them together.

The bottom outer ends of the roof sheets extend beyond the like end of the carlines and overlap the top ends of the side sheets as well as 45 the top margin of the side plate flange 19, a line of rivets 56 securing the parts together. Also rivets 57 are employed to extend through the outer end parts of the roof sheet and the web of the associated carline along with the web 31 of the 50 associated knee brace.

The opposite end margin of the roof sheets are formed to follow the flanges of the ridge member 14 to act as a flashing to insure a watertight connection for the ridge.

When two completed units 10-10 are in operative position upon a car underframe, the flanges 20 of the two ridge members abut each other and a cap strip 58 is applied thereto and to the flashing margins of the roof sheets of both units 10. Thereafter rivets 59 are inserted through registering openings in the side flanges of the cap strip, the flashing margins of the roof sheets and the flanges 20 of the members 14 to 60 secure them together. The free margins of the 65 side flanges of the cap strip are flared outwardly so that they will not bite into the flashing flanges of the roof sheet in the application of the cap piece. To further connect the abutting ends of the carlines of both units 10 together, splice bars 70 60 are employed. These splice bars are of inverted channel cross section and fit within the like cross section of the abutting ends of the associated carlines. The splice bars 60 include side flanges 61 which engage the inner faces of the 75

flanges 27 of the carlines and rivets 62 pass through the respective flanges to secure the parts rigidly together.

Of course, each unit 10 has an opening therein for the usual door (not shown). Such an opening is defined at each side by an angle bar 63.

The margins of the side sheets adjacent the door openings are devoid of any stiffening rib but overlap the outer face of the element 63 and 10 are suitably secured thereto. At each end of the unit 10 is an end rib 64 of angle bar, with one flange 65 overlapping and secured to the associated end margin of each end sheet.

When two units 10-10 are mounted upon a 15 car underframe, the other flange of the corner rib 64 overlaps the associated margin of the ends 11-11 and are riveted thereto. Said ends carry upright furring strips 66 to which the end lining is secured. In each corner, between the units 10 20 and 11 is a corner furring strip 68 at which the linings 44-67 meet and to which they are suitably secured.

It is apparent that each unit 10 is a unitary structure, which when made as described, is relatively light in weight, but is strong and rigid. It cannot warp or twist out of shape either in the handling thereof as when shipped from its place of manufacture to its place of assembly upon an underframe, or when in use on the underframe of 30 a railway car.

While in describing the invention I have referred in detail to the form, arrangement and construction of the various parts thereof, the same is to be considered only in the illustrative 35 sense so that I do not wish to be limited thereto except as may be specifically set forth in the appended claims.

I claim as my invention:

1. In a railway car body, means providing a 40 metallic body side sill including a vertical part and a horizontal part, a riser plate having its outer face arranged in the plane of the outer face of the vertical part of the sill and having its bottom margin bent inwardly so that its bottom edge engages upon the horizontal part of the sill in a plane spaced inwardly from the said face of said vertical part so as to define a groove, a line of weld in said groove to secure the riser plate to the sill member, and a metallic sheathing having a bottom margin overlapping the top margin of the riser plate and secured thereto.

2. In a railway car body, a side plate including a horizontal web, an upwardly directed outer flange and a downwardly directed inner flange, a carline having a part attached to a part of the side plate, a roof sheet secured to the carline, and a side sheet, said roof sheet and side sheet having overlapping parts arranged above the web and secured to the outer flange of the side plate.

3. In a railway car body, a side plate having a horizontal web, an upwardly extending outer flange and a downwardly extending inner flange, a carline of inverted channel cross section and including side flanges, end portions of which are 65 attached to said inner flange of the side plate, a roof sheet secured to the carline and a side sheet, said roof sheet and side sheet having overlapping parts secured to said outer flange of the side plate.

4. In a railway car, a side plate having inner and outer flanges, a carline of inverted channel cross section and including a web and side flanges with outturned margins and which margins are attached to the inner flange of the side plate, a 70 roof sheet secured to the carline, a side sheet, the

side sheet and the roof sheet having overlapping parts secured to the outer flange of the side plate, and a bracing knee between said web of the carline and said inner flange of the side plate.

5. In a railway car, a side plate having an upwardly extending outer flange and a downwardly extending inner flange, a carline of inverted channel cross section and including a web and side flanges, end portions of which are attached to the inner flange of the side plate, a roof sheet secured to the carline, a side sheet, said roof sheet and side sheets having overlapping parts secured to said outer flange of the side plate, and a bracing knee having a part engaged in and secured to the web of the carline and having another part secured to said inner flange of the side plate.

6. In a railway car body, a side plate having inner and outer flanges, a carline having a part attached to said inner flange of the side plate, a roof sheet secured to the carline, a side sheet, said roof sheet and side sheet having overlapping parts secured to the outer flange of the side plate, a bracing knee between a portion of the carline and the said inner flange of the side plate, and a bracing element connecting a part of the side sheet with said inner flange of the side plate.

7. In a railway car body, a side plate having a web and inner and outer flanges, a carline having a web and a part attached to said inner flange of the side plate, a roof sheet secured to the carline, a side sheet, said roof sheet and side sheet having overlapping parts secured to the outer flange of the side plate, a bracing knee between the web of the carline and the said inner flange of the side plate, an inwardly extending right angled 35 stiffener member integral with the side sheet, and a bracing element secured to said stiffener member and to said inner flange of the side plate respectively.

8. A unitary structure providing one side and a longitudinal half of the roof of a car body, comprising means providing a side sill with an upstanding flange-like member thereon, a side plate, a ridge member, side sheets arranged side-by-side, means providing a stiffening member along 40 one margin of certain of the side sheets, with the margins of adjacent sheets secured together in operative position, said side sheets having bottom and top margins overlapping and secured to said side plate and said upstanding flange-like 45 member respectively, carlines extending between and secured to the side plate and to the ridge member respectively, and roof sheets extending from said ridge member to and overlapping the top margin of the side sheets and a part of the 50 side plate, the side margin of the roof sheets overlapping each other upon and being secured to the carlines.

9. A unitary structure providing one side and a longitudinal half of the roof of a car body, comprising means providing a side sill, a riser plate thereon, a side plate and a ridge member, carlines between and secured to the side plate and ridge member respectively, side sheets arranged side by side, means providing a stiffening member along 65 one margin of certain of the side sheets with the lateral margins of adjacent side sheets secured together in operative relation, said side sheets having bottom and top margins secured to said riser plate and to the side plate respectively, and 70 roof sheets extending from the ridge member to and overlapping the top margin of the side sheets and a part of the side plate, and means for securing the stiffening member of the side sheets to the riser plate and to the side plate respectively, 75

the side margins of the roof sheets overlapping each other upon and secured to the carlines.

10. A unitary structure providing one side and a longitudinal half of the roof of a car body, comprising means providing a side sill, a riser plate thereon, a side plate and a ridge member, carlines between and secured to the side plate and to the ridge member respectively, side sheets arranged side by side, means providing a stiffening member along one margin of certain of the side sheets with the lateral margins of adjacent side sheets secured together in operative relation, said

side sheets having bottom and top margins secured to said riser plate and to the side plate respectively, roof sheets extending from the ridge member to and overlapping the top margin of the side sheets and a part of the side plate, means for securing the stiffening members of the side sheets to the riser plate and to the side plate respectively, the side margins of the roof sheets overlapping each other upon and secured to the carlines, and a bracing member connecting an end part of the carlines with the side plate. 5 10

OTHO C. DURYEA.
